UNITED STATES PATENT OFFICE.

EUGENE E. IHRIG AND WILLIAM H. SCHNEIDER, OF PITTSBURGH, PENNSYLVANIA,
ASSIGNORS TO UNIT COIN DEVICE MANUFACTURING CORPORATION, OF PITTSBURGH, PENNSYLVANIA, A CORPORATION OF DELAWARE.

CONTAINER FOR COINS.

Application filed January 10, 1922. Serial No. 528,253.

To all whom it may concern:

Be it known that we, EUGENE E. IHRIG and WILLIAM H. SCHNEIDER, residing at Pittsburgh, in the county of Allegheny and 5 State of Pennsylvania, citizens of the United States, have invented or discovered certain new and useful Improvements in Containers for Coins, of which improvements the following is a specification.

10 Our invention relates to improvements in containers for coins. It consists in a receptacle into which coins of any given denomination taken from a miscellaneous collection may be gathered, and in which without the 15 necessity of actual counting the aggregate value may be automatically determined. The receptacle is not bulky and affords a convenient holder for carrying coins. The invention relates itself particularly to the 20 disposal of small change in tills of retail store-keepers and of amusement places, change in church collections, etc. At the end of a day's business it is a burdensome task to sort and count and perhaps form 25 packages duly labeled of the coins resulting from the day's sales. In larger establishments there is sometimes found complicated and expensive machinery for doing this work, but in smaller establishments there is 30 a need, to the meeting of which our invention is addressed.

The accompanying drawings show a coin container embodying our invention. Fig. I is a view of it in side elevation; Fig. II is a 35 view in vertical section; Fig. III is a rear elevation; Fig. IV is a top plan view when the container is closed; Fig. V is a top plan view of it when open; and Fig. VI is a view in cross section, on the line VI—VI, Fig. I.

40 The container consists essentially of a body and a guard member. These really are in substance and effect two partial cylinders 1 and 2 pivoted together to rotate relatively on their common axis. The body member 1 is manifestly a part cylinder, as will clearly be perceived on comparing Figs. I and VI; guard member 2 is nothing more than a bar, but considering its orbit of rotation (indicated in dotted lines, Fig. VI) 45 it is after all a part cylinder. These two cylinder parts when swung to open position (Fig. V) still do not in their aggregate peripheral extent exceed a half cylinder. In

deed, in this case they make up something less than a half cylinder. It is not prohibitive of the enjoyment of our invention that these parts should exceed in the aggregate a half cylinder, but ordinarily they will together approximate that extent.

55 Means are provided for locking the two parts 1 and 2 against relative turning when the guard member 2 is in coin retaining position, that is to say when the container is "closed"—the position of Fig. IV. And as is there clearly shown, the bar then stands 60 diametrically opposed, center line opposite center line, to body member 1. These locking means are preferably automatic, so that the closed container locks itself and stays 65 locked until the guard bar is released to 70 swing to open position. Such a lock may consist of a tongue 3 of spring steel extending from guard member 2 across one head 75 of body member 1, and of a properly sunk groove 4 in the head of the body member, into which tongue 3 springs. The parts 80 may be so proportioned, as by a bevel *a* on the rim of body member 1, that the tip of the tongue 3 will when in locked position protrude sufficiently to be engaged by a finger nail and lifted, preparatory to swinging the guard member to open position.

85 Along guard rail 2 slides a follower block 5 adapted to overlie a stack of coins C arranged within the carrier and to secure 90 them against displacement. This follower block slides freely on the rail in one direction (downward, Fig. II) but sliding in opposite direction is resisted by a small spring-backed dog 6, provided with a shoulder 7. The spring backing in this case consists in 95 an attenuated rearward extension of the body of the member 6 itself. This extension being of elastic metal, affords the spring backing alluded to. The user catching shoulder 7 under a finger nail may raise 100 dog 6, and when the dog is raised the follower block 5 will slide freely, up as well as down.

Externally one of the members 1 and 2, 100 conveniently the body member, may be graduated, as shown in Figs. I and III, to afford indication of the amount contained in the carrier.

We find that there is no variation in the 105 thickness of coins consequent upon use such

as to disturb or render inaccurate such a ready means of determining aggregate value, where the total number of coins piled together does not exceed fifty say.

5 The mode of use, and the advantages of use are apparent. The user supplied with carriers of various sizes for various denominations of the coins in use, and with a sufficient number of carriers of each size, 10 takes from a miscellaneous collection of change all the cents, or nickels, or dimes, and, without counting drops them easily in piles in the opened containers. When a container is filled it may be closed and another empty one of the same size taken up. 15 Each container holds when full a certain number of the coins of the size for which it is made, and of course when full contains money to a known value. The user emptying his till packs his containers, and when he is 20 done, he can almost at a glance perceive the exact amount of money he has, and, in addition to that, he has the coins sorted and packed in convenient form for handling, 25 and the value of each package is immediately apparent.

We are content here to show the essential element in which our invention is found. Manifestly such an element or a plurality 30 of such elements may, if for any reason the doing so is thought desirable, be built into a larger or more complicated structure.

In the foregoing description we have tacitly assumed that there will be a container of distinctive size for coins of each 35 denomination, and of course this will be the preferred state of things. However it is quite possible within limits, to use a relatively large container for a relatively small 40 coin—for instance, a container primarily intended for cents may be used to receive dimes. In Figure III we show the container graduated by two scales one indicating cents, the other indicating dimes. This 45 small modification of the practice of the invention will be understood without further detailed explanation.

We claim as our invention:

1. A coin container consisting of two coin-retaining members, one being an incomplete cylinder and the other a guard rail rotatable on the cylindrical axis over the open side of the incomplete cylinder, and a follower adapted to slide upon one of said members and engage the top of a stack of 55 coins within.

2. A coin container including two cylinder parts relatively rotatable on their common axis and in their combined peripheral extent not exceeding a half cylinder, and manually releasable means for positively securing the parts in opposite relative positions.

3. A coin container consisting of an incomplete cylinder and a guard rail rotatable 65 on the cylindrical axis over the open side of the incomplete cylinder and means for securing the rail in intermediate position in the range of rotation including a spring tongue fitting into a recess and adapted to 70 be manually lifted therefrom in effecting release.

4. A coin container consisting of an incomplete cylinder, a guard rail rotatable on the cylindrical axis over the open side of 75 the incomplete cylinder, and a stop adapted to slide upon said guard rail.

5. A coin container consisting of an incomplete cylinder, a guard rail rotatable on the cylindrical axis over the open side of 80 the incomplete cylinder, a stop adapted to slide upon said guard rail, and a retractable spring impelled check borne by said stop and normally engaging said rail and adapted to secure the stop against sliding in one 85 direction.

In testimony whereof we have hereunto set our hands.

EUGENE E. IHRIG.

WILLIAM H. SCHNEIDER.
